[57] **ABSTRACT**

An open-end spinning machine in which the turbine housing is by means of a control lever and a crank drive operatively connected to the control lever movable along a straight path in the axial direction of the turbine housing and is provided with locking means responsive to a predetermined stroke of the turbine housing along said straight path to lock the control lever to the turbine housing and the crank drive whereupon the turbine housing is by means of the control lever pivotable about a pivot shaft extending in the longitudinal direction of the machine, for yielding easy access to the interior of the turbine housing.

SHEET 2 OF 3

FIG. 2

FIG. 3

PIVOTING DEVICE FOR TURBINE HOUSINGS OF OPEN-END SPINNING MACHINES

The present invention relates to a pivoting system for turbine housings of open-end spinning machines in which the turbine housing with the spinning turbine mounted therein is pivotable about a horizontal pivot axis extending parallel to the machine front from its substantially vertical position of operation, in which the turbine housing is in upward direction adjacent to the housing for the opening-up roller, and in which the opening-up roller which is coaxially arranged with regard to the spinning turbine extends from above into the spinning turbine.

According to a heretofore known pivot system, the turbine housing is pivotable about a pivot axis in downward and rearward direction which pivot axis is located behind the spinning turbine at the level of the opening-up roller. The pivot angle is limited to 30° because the turbine housing would otherwise hit the withdrawal-delivery system which, in view of the fact that the overall height of the open-end spinning machine is to be held low, follows the spinning turbine at a slight distance relative thereto.

The heretofore known pivot system is simple inasmuch as the removal of the spinning turbine from the opening-up roller extending thereinto is effected during the first phase of the pivot movement. However, the pivot angle is merely sufficient to clean the opening-up roller or to exchange the same. On the other hand, the necessary accessibility for a quick cleaning of the spinning turbine itself and for a fast exchange of the spinning turbine together with the bearing means therefor is lacking with this pivot system. If it is desired to exchange the spinning turbine or quickly to clean the same, the entire turbine housing has to be removed from the machine which requires considerable time and work. This drawback is also inherent in various other attempts of solving the problem involved.

It is, therefore, an object of the present invention to provide a pivot system for turbine housings of open-end spinning machines which will make it possible in a simple manner quickly to clean the spinning turbine and to exchange the spinning turbine with the bearing means whenever necessary.

This object and other objects and advantages of the invention will appear more clearly from the following specification in connection with the accompanying drawings, in which:

FIG. 1 illustrates in side view and partly in section a turbine housing of an open-end spinning machine with a pivot system according to the invention; FIG. 1 showing the turbine housing in its position of operation.

FIG 2 is a simplified rear view of FIG. 1 as seen in the direction of the arrow II, but on a considerably larger scale than that of FIG. 1.

FIG. 3 is a side view similar to that of FIG. 1 with the turbine housing likewise seen in side view and displaced axially downwardly into a position from which it is subsequently pivoted into the dot-dash position.

The pivot system according to the present invention is characterized primarily in that the turbine housing which is pivotable out of the plane of the machine front is adjustable relative to the pivot axis located below its position of operation prior to and following the pivoting out of and into the position of operation in the direction of the axis of the spinning turbine in downward

and in upward direction along guiding means arranged at the bottom side of the housing for the opening-up roller which guiding means in downward direction project beyond the opening-up roller. The pivot system according to the present invention is furthermore characterized in that the turbine housing has associated therewith an actuating lever rotatable on the pivot axis of the turbine housing in such a way that during the rectilinear adjusting motions of the turbine housing the lever forms with the turbine housing a crank drive through the intervention of a connecting element which serves as connecting rod and has one end in spaced relationship to the pivot axis linked to the actuating lever and has its other end linked to the turbine housing, the lever forming with the turbine housing a rigid pivotable unit during the pivoting movements of the turbine housing.

The pivot system according to the present invention has various advantages. Thus, by arranging the pivot axis within the region below the position of operation of the turbine housing, it will be assured that the housing will be pivoted substantially in a direction transverse to the direction of the axis of the spinning turbine. In this way it will be possible that, already after the spinning turbine has been pivoted through only a relatively small pivot angle, the spinning turbine will be freely accessible for a quick cleaning and for a quick exchange together with its bearing means. This way of exposing and making accessible of the spinning turbine is effected in a simple manner inasmuch as by means of one actuating lever the turbine housing is first withdrawn out of the range of the opening-up roller by a straight line movement and is then pivoted out of the plane of the machine front.

According to a further development of the invention, the outward pivoting and the return pivoting of the turbine housing can be further simplified by pressing the turbine housing in its position of operation by one or more spring means resting against the pivot axis and forming with the turbine housing a pivot unit against the housing of the opening-up roller, while the actuating lever with its crank-forming part and the connecting element linked to the actuating lever and the turbine housing and serving as connecting rod will, following the straight line adjustment of the turbine housing, be located below the guiding means on the side of the outward pivot movement and will then be located in the region of the outer dead center point of the crank drive. The spring means arrest the turbine housing in its position of operation on the housing of the opening-up roller. No special manual operation is necessary for the actuation of the arresting system. The unlocking and arresting is taken care of by the pivoting of the actuating lever.

Referring now to the drawings in detail, in the turbine housing 1 of an open-end spinning machine, of which only those elements have been shown which are important for explaining the invention, the spinning turbine 3 is by the bearing means 3a received from above and is arrested in the turbine housing by means of a clamping device 4 (not shown in detail). In its position of operation i.e., in its spinning position according to FIG. 1, the turbine housing which is open at the top is arranged adjacent the housing 7 for the opening-up roller 13, while the opening-up roller 13 which is coaxially arranged with regard to the spinning turbine extends into the latter from above.

For cleaning the spinning turbine 3 and for exchanging the spinning turbine with its bearing means 3a, it is necessary to expose the turbine housing with its upper opening. In conformity with the present invention, the turbine housing has associated therewith a new pivoting system which in a simple manner permits to expose and make the turbine housing easily accessible so that a quick cleaning and quick exchange of the spinning turbine with its bearing means will be assured.

More specifically, the turbine housing 1 is pivotable about a pivot shaft 2 which is located within the region below the position of operation of the spinning turbine and is pivotable toward the front out of the plane of the machine front 14. A straight line or rectilinear adjustability of the turbine housing with regard to the pivot axis in the direction of the axis of the spinning turbine 3 is provided. To this end, I-bolts 5 are rotatably arranged on the pivot shaft 2. The turbine housing 1 is by means of sleeves 5a rectilinearly guided in the direction of the turbine axis on the I-bolts 5.

Between the heads of the I-bolts 5 and the sleeves 5a there are arranged compression springs 6 which press the turbine housing 1, when the latter occupies its position of operation shown in FIG. 1, against the housing 7 of the opening-up roller 13 and arrests the turbine housing 1.

The outward and the return pivoting of the turbine housing 1 including the unlocking and locking on the housing 7 of the opening-up roller 13 is effected solely by pivoting the actuating lever 9 about the pivot shaft 2. The lever is associated with the turbine housing 1 in such a way that it is able to effect the straight line adjustment of the turbine housing through the intervention of a crank drive and for purposes of pivoting the turbine housing is arrestable on the crank drive.

More specifically, the arrangement is as follows. The crank disc 15 is rotatably arranged on the pivot shaft 2. A hook 10 serving as connecting rod has one end thereof linked at 16 to the crank disc 15, whereas its other end is linked at 17 to the turbine housing 1. The actuating lever 9 is with regard to the pivot shaft 2 non-rotatably connected to the crank disc 15. At the same time, however, it is pivotable in the direction of the pivot shaft 2. To this end, the actuating lever 9 has one end rotatably arranged on a plug sleeve 18 which in its turn is in tangential direction firmly connected to the crank disc 15 by a spacer member 19.

As will be seen from FIG. 2, the actuating lever 9 is continuously urged to turn relative to the plug sleeve 18 in the direction toward the turbine housing 1 by means of a tension spring 11 which is located between the actuating lever 9 and the crank disc 15 and which has been omitted in FIGS. 1 and 3 in order not unnecessarily to overload these figures. This arrangement is such that the actuating lever 9 during its pivoting movement from the position shown in FIG. 1 in counterclockwise direction latches automatically into the recess 12 of the housing. As a result thereof, the actuating lever 9 will with regard to the pivot shaft 2 be non-rotatably connected to the turbine housing 1.

The outward and return pivoting of the turbine housing is in conformity with the pivoting system of the present invention effected in the following manner. For pivoting the turbine housing 1 out of its position of operation or out of its spinning position shown in FIG. 1, the actuating lever 9 is pivoted in counterclockwise direction. During this operation, the turbine housing

rectilinearly adjusted in downward direction along the guiding cams 8 by means of the above mentioned crank drive in the direction of the arrow 21. During this withdrawing movement, the guiding cams 8 act counter to a pivoting moment which acts in the direction of the outward pivoting direction and is caused by the springs 6. This pivoting moment decreases as a result of the movement of the joint point 16 toward the outer dead center point of the crank drive and at the instant when the turbine housing leaves the guiding cams 8 equals zero for all practical purposes.

After a certain pivoting angle, at which the turbine housing 1 has been withdrawn according to FIG. 3 to a point below the guiding cams 8 and the joint point 16 has in the specific embodiment shown moved somewhat beyond the outer dead center point, the actuating lever 9 will, due to the tension spring 11, automatically latch into the recess 12 of the housing. Lever 9 now forms with the turbine housing a rigid pivoting unit so that during a further pivoting of lever 9 the turbine housing will be pivoted in the direction of the arrow 22 of FIG. 3.

During the return pivoting of the turbine housing the actuating lever 9 remains locked in recess 12 until the turbine housing engages a rear abutment which in the specific embodiment shown is formed by the suction head 20. Thereupon, lever 9 is against the force of spring 11 pivoted out of the recess 12 and is pivoted in clockwise direction. Inasmuch as the crank drive first operates in the region of the outer dead center point, spring 6 will during the movement of the turbine housing onto the guiding cams 8 practically not exert a pivoting moment in the outward pivoting direction.

Basically it is possible to arrange the devices which connect the turbine housing with the pivot shaft, when viewed in the longitudinal direction of the machine, laterally of the devices which follow the spinning turbine. As will be evident in particular from FIGS. 1 and 3, an especially advantageous design of the invention consists in adjustably mounting the turbine housing 1 for adjustment in the direction of the axis of the spinning turbine 3. This way of mounting the turbine housing 1 is effected through the intervention of a pivot arm 24 which is cranked around the delivery system 23. The pivot axis is within the region below the delivery system 23 offset with regard to the direction of the axis of the spinning turbine, when the latter is in its position of operation, toward that side which is remote from the plane of the machine front 14. Furthermore, the hook 10 serving as connecting rod is linked to that part 24a of the cranked pivot arm which faces toward the pivot shaft 2. The region below the spinning turbine or spinning turbine housing remains completely freely accessible.

A further advantage of the arrangement according to the present invention consists in that with the lateral pivoting the turbine housing is displaced simultaneously in downward direction whereby the turbine housing reaches a level which is even more easily accessible for servicing.

Another advantageous design of the invention consists in that the guiding surfaces 8a of the guiding cams 8 arranged on the outward pivoting side (arrow 22) extend parallel to the axis of the spinning turbine 3 when the latter is in its position of operation and parallel to the longitudinal axes of the I-bolts 5. The engaging surface 20a of the suction head 20 for the turbine housing

1 is inclined downwardly away from the axis of the spinning turbine 3 when the latter is in its position of operation. During the straight line downward and also during the upward adjustment, the turbine housing 1 is guided by means of the guiding cams 8 which are arranged on the outward pivoting side. In this connection the turbine housing with its abutment surface 25 associated with the suction head 20 is by a displacement parallel to itself lifted off from the abutment surface 20a of the suction head or is brought into engagement therewith. In this way a tight fit of the turbine housing on the suction head will be assured.

It is, of course, to be understood that the present invention is, by no means, limited to the specific showing in the drawings but also comprises any modifications within the scope of the appended claims.

What is claimed is:

1. An open-end spinning machine, which includes: a turbine housing open at its upper end, a spinning turbine journaled in said turbine housing, a housing means for an opening-up roller, said housing means being arranged above and closing up said turbine housing when said turbine housing is in its position of operation, a pivot shaft extending in the longitudinal direction of said machine at a level lower than said turbine housing, said turbine housing being movable relative to said pivot shaft from a first position in which said turbine housing is in engagement with said housing means successively along a straight first path in the axial direction of said turbine housing and along a curved second path around said shaft and vice versa, guiding means projecting from said housing means and extending in axial direction of said turbine housing while slidingly engaging a portion of said turbine housing for guiding the same along said straight first path, crank drive means connected to said turbine housing, control lever means connected to said crank drive means and operable to cause said crank drive means to move said turbine housing away from said housing means along said first path and to disengage said turbine housing from said guiding means, and means responsive to said turbine housing having disengaged said guiding means at

the end of said first path to lock said crank drive means and to establish a rigid connection between said turbine housing and said control lever to thereby permit movement of said turbine housing along said second path about said pivot shaft.

2. A machine according to claim 1, in which said turbine housing has a crank arm pivotally supporting said turbine housing on said pivot shaft, and in which said crank drive includes a crank disc rotatably connected to said pivot shaft and also includes a connecting member having one end portion pivotally connected to said crank arm.

3. A machine according to claim 2, which includes spring means supported by said pivot shaft and operable in the position of operation of said turbine housing to press said turbine housing against said housing means, said spring means forming a pivotal unit with said turbine housing.

4. A machine according to claim 1, in which said control lever means and said crank drive means are kinematically so connected to each other as to occupy their outer dead center position when said turbine housing is in its position of operation.

5. A machine according to claim 1, which includes a suction head arranged adjacent to and having an engaging surface thereof in engagement with said turbine housing when the latter is in its position of operation, and in which at that side of the machine toward which the turbine housing is pivotable said guiding means includes a guiding element having its guiding surface extending substantially parallel to the axis of said turbine housing when the latter is in its position of operation, whereas said suction head surface which engages said turbine housing when the latter is in its position of operation is inclined in a direction away from the axis of said turbine housing when the latter is in its position of operation.

6. A machine according to claim 5, in which said suction head is at least approximately diametrically opposite said guiding element.
